GEORGE P. LEWIS, OF FOREST HILLS, AND RAYMOND E. SABIN, OF FLUSHING, NEW YORK

PORTABLE MOTION PICTURE SCREEN

Application filed February 14, 1930. Serial No. 428,296.

This invention relates to portable projection screens for motion pictures.

The principle object of our invention is to provide an apparatus of simple, inexpensive and durable construction embodying a portable element with which a rigid frame, including a screen surface, is slidably associated, which element is constructed and adapted to protect the screen surface during the transportation or non-use of the screen, and also to serve as an efficient floor stand or pedestal to support the screen frame vertically and at a proper elevation above the element when the apparatus is in actual use in connection with a projecting machine, thus obviating the necessity of employing a table or other extraneous support for the screen.

A further object of the invention is to provide an apparatus whereof the supporting element comprises a narrow rectangular container into and from which the screen frame can be slidably moved with facility, the construction being such that the screen surface is protected from contact with the walls of the container and also from contact with the hands of the operator during the respective steps of shutting and exposing the screen.

A further object of the invention is to provide an apparatus wherein the screen frame serves as a closure for the container.

A further object of the invention is to provide a construction whereby a single handle may be utilized as a medium to raise and lower the screen frame and also to carry the apparatus when the screen frame is within the confines of the container.

With these and other objects in view our invention embodies novel structural features and combinations of parts which will be hereinafter described; the scope of the invention then being defined in the appended claims.

In the drawings—

Figure 1 is a perspective view of a motion picture screen embodying a preferred form of our invention showing the screen frame supported in elevated position.

Fig. 2 is a similar view showing the container with the screen frame confined therein.

Fig. 3 is a transverse vertical section through the apparatus in closed condition.

Fig. 4 is a transverse horizontal section, partly in plan, of the upper portion of the container, with the screen frame in raised position, the spaced top bars of the container being partially broken away to show the relation thereto of a stop member on the screen frame.

Fig. 5 is a transverse vertical section, as on the line 5—5 of Fig. 1.

Fig. 6 is a sectional detail of a lower end portion of the container, showing one of the pivotal supporting feet therefor.

Fig. 7 is a bottom view of one of the supporting feet.

Fig. 8 is a perspective view of an upper corner of the container and the adjacent portion of the extended screen frame supported thereon.

Referring to the drawings, A designates a rigid rectangular screen frame, and B designates a casing structure of proper size to receive and protect the frame, yet permit the frame to be bodily lifted above the structure and supported thereby, as a floor stand or pedestal, with the screen surface in proper position to receive the pictures from a projecting machine.

The screen frame preferably comprises end bars 10 and upper and lower cross bars 11, 12, respectively, and contains screen material 13 of paperboard or other sheet material. One surface of the material may be white, and the other may be coated with aluminum in order that either surface may be used to receive the pictures, as desired.

In the present instance the structure B comprises a narrow rectangular case open along the top. This case includes spaced-apart vertical end bars 14 provided in their inner sides adjacent their upper ends with guide grooves 15 to receive and guide the vertical end bars 10 of the screen frame. The bars 14 are connected at their lower ends by a cross-bar 16, which constitutes the bottom of the case, and at the top by a pair of parallel horizontal bars 17 which afford between them a slot or opening of proper width and length to permit the frame A to be extended upwardly from or be enclosed in the case, as desired; it being noted that the end bars

10 of the screen frame are slightly extended below the lower cross-bar 12 to afford supports which are seated in the upper guide grooves of the end bars 14 when the frame is 5 fully raised, and also bear on the bottom bar 16 of the case when the frame is enclosed.

The respective side walls 18 of the case 10 preferably comprise sheets of fibrous substance, such as paperboard, and the whole 15 may be exteriorly covered with suitable fabric, thus presenting a neat and attractive structure of substantial strength and relative lightness.

The case is equipped with suitable means 15 to support the case and the extended screen frame in upright position on the floor, such means in the present instance embodying a pair of pivoted basal members 19 which may be swung longitudinally of the case so as 20 to be out of the way, as seen in Fig. 2, or be swung cross-wise to afford supporting feet for the case and the elevated screen, as 25 seen in Fig. 1. The pivots for the members 19 comprise screws 20 which are inserted in the bottom bar 16 of the case, which bar has 30 affixed to its inner surface suitable reinforcing blocks 21 which receive the screws. The under surfaces of the members 19 are 35 longitudinally recessed to accommodate spring pressure plates 22 against which bear the heads of the respective screws, such plates thus exerting sufficient pressure on the members to maintain them securely in their respective active and idle positions.

40 Means to limit the upward extension of the screen frame with respect to the case is provided, which means preferably comprises a block 23 which is secured to the mid-portion of the lower cross-bar 12 of the screen, and 45 is arranged to abut against the undersides of the spaced top bars 17 of the case when the screen frame is fully extended. The screen frame and the case are assembled by manually springing the bars 17 apart mid-way of their ends to permit the passage of 50 the stop-block 23 between the bars, which bars, when the elements are associated, are released and permitted to resume their normal parallel relation.

55 To sustain the screen frame in its elevated position, the end bars 10 of the frame are provided with suitably-located latches which co-act with the case when the screen frame is fully raised. Each of these latches 60 preferably comprises an angular strip of spring metal 24 whereof one limb is secured, as at 25, to the adjacent end bar 10 of the screen frame and the other limb is movable into and from an aperture 26 in such bar. 65 When the screen frame is fully raised above the case the latches spring normally outward and bear upon the opposing end bars 14 of the case, as seen in Fig. 1. When it is desired to enclose and protect the screen frame, 70 as seen in Fig. 2, the latches are manually 75

pressed inward to escape the inner edges of the bars 14, and the frame is pushed down to the bottom of the case, whereupon the top bar 11 of the screen frame registers with and affords a closure for the open top of the case. 70 The inner walls of the end bars 14 are provided with longitudinal grooves 27 which terminate short of the tops of the bars, as seen in Fig. 3. These grooves receive the latches 24 when the screen frame is initially entered in the case, and co-act with the latches to guide the frame vertically, the frame bars protecting the screen surfaces from frictional contact with the case.

The top bar 11 of the screen frame is provided in its mid-portion with an upwardly extending handle fixture 28 whereby the screen frame can be readily raised and lowered with respect to the case without any liability of the screen surfaces being touched 80 by the user, which handle also facilitates the carrying of the case and the confined screen. When the screen is encased a strap 29 which is pivoted on the outer side of one of the top bars of the case, as at 30, is passed through 85 the handle and secured by a snap fastener 31 on the outer side of the companion top bar of the case, thus holding the screen frame within the case and permitting the case and 90 contents to be readily carried by means of 95 the handle. (See Fig. 2.)

We do not limit our invention to the details of construction herein disclosed, as the structure may be modified within the principle of the invention and the scope of the 100 appended claims.

We claim—

1. A combined portable motion picture screen and a casing therefor, the casing having a bottom member and end members slightly wider than the thickness of the screen, side members connected to the bottom and end members, cooperating guiding means on the screen and the end members to permit the screen to slide in the casing, said screen being arranged to be extended above the casing, means for holding said screen in its extended position, and a pair of basal members pivoted to the bottom member arranged to extend transversely of the casing to form feet for the casing when the screen is extended and to extend parallel to the bottom member when the casing is used as a carrying case for the screen. 110

2. A combined portable motion picture screen and a casing therefor, the casing having a bottom member and end members slightly wider than the thickness of the screen, a top member on each side of the screen connected to the end members, side members connected to the bottom, top and end members, cooperating guiding means on the screen and the end members to permit the screen to slide in the casing, said screen being arranged to be extended above the casing, 120 125 130

- means for holding said screen in its extended position, and a pair of basal members pivoted to the bottom member arranged to extend transversely of the casing to form feet for the casing when the screen is extended and to extend parallel to the bottom member when the casing is used as a carrying case for the screen. 5
3. A combined portable motion picture screen and a casing therefor, the casing having a bottom member and end members slightly wider than the thickness of the screen, a top member on each side of the screen connected to the end members, side members connected to the bottom, top and end members, a stop on the screen arranged to engage the top members when the screen is extended, cooperating guiding means on the screen and the end members to permit the screen to slide in the casing, said screen being arranged to be extended above the casing, means for holding said screen in its extended position, and a pair of basal members pivoted to the bottom member arranged to extend transversely of the casing to form feet for the casing when the screen is extended and to extend parallel to the bottom member when the casing is used as a carrying case for the screen. 20
- 25
4. A combined portable motion picture screen and a casing therefor, the casing having a bottom member and end members slightly wider than the thickness of the screen, side members connected to the bottom and end members, there being guide grooves in the end members for the screen, an outwardly movable spring latch on each edge of the screen near the lower end thereof arranged to engage the upper ends of the end members to support the screen when extended, and a pair of pivoted basal members on the bottom member. 30
5. A combined portable motion picture screen and a casing therefor, the casing having a bottom member and end members slightly wider than the thickness of the screen, side members connected to the bottom and end members, there being guide grooves in the end members for the screen, an outwardly movable flat spring latch on each edge of the screen near the lower end thereof arranged to engage the upper ends of the end members to support the screen when extended, there being a latch receiving groove in each end member below the upper end thereof opening into the guide groove, and a pair of pivoted basal members on the bottom member. 35
6. A combined portable motion picture screen and a casing therefor, the casing having a bottom member and end members slightly wider than the thickness of the screen, side members connected to the bottom and end members, there being guide grooves in the members for the screen, an out-
- wardly movable spring latch on each edge of the screen near the lower end thereof arranged to engage the upper ends of the end members to support the screen when extended, a pair of pivoted basal members on the bottom member, means for securing the screen in the casing, and a carrying handle on the top of the screen. 40
